UNITED STATES PATENT OFFICE.

CYPRIEN SOUCY, JR., OF MANCHESTER, NEW HAMPSHIRE.

BICYCLE.

SPECIFICATION forming part of Letters Patent No. 684,469, dated October 15, 1901.

Application filed March 27, 1900. Serial No. 10,875. (No model.)

To all whom it may concern:

Be it known that I, CYPRIEN SOUCY, Jr., a citizen of the United States, residing at Manchester, in the county of Hillsboro and State of New Hampshire, have invented certain new and useful Improvements in Bicycles; and I do hereby declare the following to be a full, clear, and exact description of the invention, such as will enable others skilled in the art to which it appertains to make and use the same.

This invention relates to the forks and driving-gear of a bicycle, the object being to construct a bicycle-frame which shall be yielding forward and back of the crank-shaft, thus dispensing with the necessity for using pneumatic tires.

Many riders would prefer to ride upon some sort of a yielding seat or frame if they could get the comfort afforded by relief from the severe jar imparted to a rider of a rigid frame and saddle in passing over rough roads or through roughly-paved city streets without the accompanying disadvantages of such constructions.

The objections which are commonly raised against spring saddles or spring seat-posts are that the distance between the crank-shaft and the saddle is constantly varying, thus making it more tiresome and difficult for a rider to propel his bicycle.

In bicycle-frames as now constructed the distance between the crank-shaft and the ground is at all times equal; but by constructing a frame in which the distance from the crank-shaft to the saddle is unchangeable (except as the saddle-post may be adjusted according to the requirements of a rider) and providing yielding wheel-forks the objections against the use of springs of any form heretofore mentioned are effectively overcome.

The invention involves the use of a pivotally-connected and spring-actuated rear fork and a spring-actuated front fork, permitting the perch (carrying with it the crank-shaft hanger and seat) to move vertically toward and away from the ground; but this construction alone without any change in the form of driving-gear would cause a constantly-varying movement of the crank-shaft forward or backward either faster or slower than its

natural rotative course relative to the rotation of the driving-wheel at any given speed, and this jerky movement of the crank-shaft, however slight it might be, would be sufficient to be felt by a rider having his feet upon the pedals. Hence my invention consists, broadly, in an improved construction for bicycle-frames whereby the stroke of the leg of a rider may be at all times equal, while his body may be supported in a manner equivalent to the ease and comfort afforded by a spring-saddle or spring seat-post, and in providing a novel form of driving-gear by which said results are attained.

The invention will be fully set forth in the following specification and claims and clearly illustrated in the drawings accompanying and forming a part of the same, of which—

Figure 1 is an elevation showing my improved bicycle frame and gearing with broken portions of the wheels. Fig. 2 is an enlarged detail view showing a portion of my improved front fork and its spring-actuated connection. Fig. 3 is a broken front elevation of the same. Fig. 4 is an enlarged broken sectional elevation showing the spring-adjusting mechanism adapted to act upon the rear fork. Fig. 5 is an enlarged broken rear elevation of those parts shown in Fig. 4. Figs. 6 and 7 are detailed broken elevations of a portion of the front fork. Fig. 8 is a detail of a portion of the front fork shown in central vertical section.

Similar reference-letters denote corresponding parts in all the views.

A represents the wheels. B is the upper tube, C the lower tube, and D the head or socket, carrying the front fork and to which one end of the tubes B C are brazed in the usual manner.

E is the perch, and F the crank-shaft-hanger, to which the lower end of said perch and the tube C are attached by a brazed joint, the upper end of said perch being connected to the rear end of the upper tube B by brazed union.

G is the rear fork, which is pivotally connected at g to the perch E and at a point above the bracket F, as shown.

H represents the rear-fork stay, which is pivotally connected at h to the rear fork, the upper end of said stay being loosely mounted

and capable of longitudinal movement within a steel casting I, said casting being brazed to the perch E and containing novel spring mechanism, to be hereinafter explained.

5 The normal position of the rear fork G is horizontal, as seen in Fig. 1; but its free end, to which the stay H is attached, may yield upward against the pressure of some suitable spring, with which the upper end h' of the stay 10 H may be connected, and the front fork is likewise so constructed that it may be acted upon by a suitable spring. The spring mechanism for each fork may be of different construction; but in the present drawings I show 15 practically the same spring mechanism for both forks, and this consists in or comprises helical springs adapted to rotate a peripherally-grooved cam and a chain or wire cable connecting the grooved cam with either the 20 movable portion of the front fork or the upper end h' of the rear-fork stay H, as shown. By the use of such a cam the leverage applied to the springs is shortened as the load increases, and therefore the tension of the 25 springs, which is naturally increased by the increase in weight of one rider over another, may be made to automatically adjust itself to the demands of various riders.

The bracket I, which incloses the spring 30 mechanism, may be conveniently formed by casting it of steel, and it is provided with a perforation i , in which the upper end h' of the stay H finds its bearing, and at one side with a detachable plate or cover i' , which may be 35 secured thereto by screws, as seen in Figs. 1 and 4. Hollow projections i^2 are formed one upon the bracket I and one upon the cover i' and disposed one opposite to the other, the ends of said projections being perforated for 40 the reception of a shaft J, and upon this shaft is mounted a sleeve K, to the central portion of which is attached a grooved cam L. At each side of said cam and upon the sleeve K is placed a helical spring M, one end of each 45 spring being connected at l to the cam and the other end being connected at i^3 to the projection i^2 of the bracket I, and a chain or wire cable N has one of its ends attached at l' to the grooved cam and at the other end to the 50 upper end h' of the stay H, as at h^2 , the relative position of the cam to the top of the stay being such as to cause the springs M to be wound or their tension increased with the upward movement of said stay within the 55 bracket, and vice versa, this increase of tension being somewhat equalized to the weight of various riders by the use of the grooved cam over which the chain or cable N passes to the upper end h' of the stay H.

60 The front fork comprises an inside and outside member, respectively, O P, the former carrying the front wheel and being adapted to move vertically within the latter. The inside fork O has a head o, provided with a longitudinal groove o' in its front face, and said head fits within the hollow head p of the out-

side fork P. Said outside fork has bearings P' at its lower end, as shown in Fig. 6, to which the inside fork is fitted, and said outside portion of the front fork carries at its upper end 70 a plate Q, secured thereto by screws, as seen in Fig. 3, and upon this plate are formed hollow projections q , extending from opposite sides of a recess or cam-chamber q' , and in the hollow projections q is mounted a shaft R, 75 upon which is loosely mounted a sleeve s, provided at its central portion with a cam S, having an annular groove in which a chain or cable T may rest, said cable being connected at one end to said cam, as at s' , and at the 80 other end to the upper end of the groove o' of the head o of the inner fork, as at o^2 . (Shown best in Fig. 2.)

I will now speak of the driving mechanism. If the driving-chain U should pass around a 85 small sprocket V on the rear wheel and thence around a larger sprocket on the crank-shaft, a jerky motion of the pedals would be felt by a rider quite as severely as when riding an ordinary bicycle provided with a spring saddle or seat-post, and to avoid this I employ a small sprocket V', which is mounted upon the pivotal connection g of the rear fork G and at a point above the crank-shaft, said sprocket V' having teeth equal in number to 95 those of the sprocket V, and upon this sprocket I provide side teeth v, which are adapted to engage teeth or rolls x, projecting from the side of a large driving-gear X, which is mounted upon the crank-shaft W, the number of 100 the teeth or rolls x upon this gear X determining whether the "wheel" shall be either "high" or "low" gear. A pair of helical springs S' are mounted upon the sleeve s, one at either side of the cam S, one end of either 105 spring being connected at s^2 to said cam and their opposite ends being connected at q^2 to either end of the hollow projections q of the plate Q, and to prevent any friction of the cable T against the lower part of the head 110 p of the fork P when the head o moves upward therein the fork P may be recessed, as at p' , to receive journal-bearings p^2 , in which to mount a shaft p^3 , carrying a friction-roll p^4 , against which the cable T will ride, the 115 foregoing construction being clearly illustrated in Figs. 2, 6, and 7.

Having described my improvements, what I claim is—

1. In a bicycle, a front fork composed of 120 two members one vertically movable within the other, a spring-actuated peripherally-grooved cam mounted upon one member, the spring for actuating said cam, and a chain or wire cable connecting the grooved periphery 125 of said cam with the movable member of said fork, substantially for the purpose set forth.
2. In a bicycle, a pivotally-attached rear fork carrying a pivoted rear stay, a bracket rigidly secured to the perch and having a perforation serving as a loose bearing for the upper end of said pivoted stay, a spring-ac- 130

tuated peripherally-grooved cam mounted in said bracket, and a chain or wire cable connecting the cam with the vertically-movable rear stay.

5 3. In a spring-frame for bicycles, means for automatically graduating the tension of the springs to the weight of various riders, comprising spring-actuated cams, whereby the

leverage applied to said springs is shortened as the tension of said spring increases.

In testimony whereof I affix my signature in presence of two witnesses.
